(54) **SPINNING COTTON**

(76) Inventor: **William Pollard**

To the Honorable Thos Jefferson, Henry Knox, Edmund Randolph, Esqrs.

The Representative & Edition of William Penn of Philadelphia especially sheweth.

That your Petitioner above ^{twelve} months ago purchased a model of a machine for Rolling & Spinning of Cotton at the expense of seven hundred pounds which was sold to him as a model of Mr. Richard Arkwright's machine and was brought into this country at the expense of vessel & cargo's having arrived on the Captain board's imprisonment & trial as soon as your Petitioner obtained it, he perceived to be made a machine (on a small scale) in just proportion in every respect to the said model but found it would not answer the purpose in consequence of this he wrote to the person he had purchased the model from on the 6th of Oct: last and informed him that your Petitioner had made a machine after the model but that it would not spin, and that as was evident some mistake had been made either by the work man or in the design, but the Gentleman having returned your Petitioner's Bond for the model without any reference to the consideration for which it was given was not thought proper to give your Petitioner with an answer but as he is informed he has resigned the Bond over to a third Person. Your Petitioner having been bid in post a manufacturer & being some judge of spinning & of yarn made such alterations in the machine from time to time as were consistent with his own judgment & hath now brought a machine to perfection for the Rolling and spinning of Cotton; that the model so purchased was complete as he arrived it and that of your Petition is also complete both are ready for inspection, the difference in them is visible and material. Your Petitioner's machine may be made to contain twenty spindles or twenty turners if the steam of water or other force which is to work them will carry that number and the said house will contain them.

In order to convey your idea of the importance of these machines your Petitioner begg'd to trouble you for your board to a copy of a statement in Cary's museum published in Philadelphia Oct: 1783, and which from his knowledge of Manchester Cotton goods he conceives to be a reasonable statement it is as follows.

On account of the Cotton Mills in Great Britain & an Estimate of the Cotton Manufactory of that Country.

One hundred and forty three cotton mills are now built & in progress in Great Britain of which nearly two thirds have been erected within these five years. Besides these there are above 20,000 hand mills or frames for spinning the slates for the twisted & spun by the water mills.

The expense of Water, taxes, &c.	\$19,575.000
Expense of hand Jennies houses buildings & auxiliary machinery	250.000
supposed at least	
The state of the raw materials & the progressive & astonishing increase of the manufacture will be best ex- plained by what follows	
The cotton & Wool applied	to the manufacture was in
to the manufacture was in	Year. it
1781. 9,161,499	\$9,600,000
1782. 11,306,300	9,900,000
1783. 9,846,179	9,900,000
1784. 11,250,238	9,930,000
1785. 17,492,888	9,900,000
1786. 16,161,867	9,600,000
1787. 22,086,666	9,300,000

From whence it appears that the cotton & wool applied to the hand and water machines in Great Britain in 1787 being 22,086,666 (worth in the raw state about \$9,930,000) was worth when manufactured \$7,500,000, yielding the immense profit to the manufacturers of the labor & fatigues of \$5,270,000.

It may be observed in the foregoing statement that the Raw Cotton & Wool is valued at about 15/- per lb. Cotton can be purchased now from 18/- to 25/- per lb. Turned and in the Southern States where young negroes recently ~~are~~ ^{are} disabled, their & slaves are put into further to their owners, they being in these cotton mills be employed to advantage, and the same operation, may be extended to the poor white inhabitants in all our large towns, and your petitioners conceive to a certain extent manufacturers which can have the aid of such machines may be compelled in this country as low as in England. One girl or boy from eight to fourteen years of age will tend from 30 to 60 spindles, & it is necessary to have a man or woman to every ten children, to keep order no certain strength is required in the spinning apartment; It may be further observed on the gen-

manufactured is only a little more than £17 1/2 pr. lb weight and calicoes are worth from £1 to 19 1/2 pr. lb when finished & corduroy, velvets, velveteens, jeans, &c. are worth from £1 to 19 1/2 pounds from £1 to 25 1/2 pr. lb so that if the statement had been made on cotton & calico in your petition we conceive that the saving to the Country would have been much more considerable. Your Petitioner therefore, prays that in consideration of the expense & trouble he has been at in procuring the model of the English machine, which nevertheless proved in a great degree useless, but more especially for the material & effectual improvement & alterations made by his discreet & judicious advice to perfect a machine which promises such extensive advantages to these United States by which he is now ready to lay a model before your court together with the model of the English machine in order that the improvements and alterations may be fully seen & understood, that your honorable board will be pleased to grant him his just and exclusive sole and exclusive right and liberty of making constructing & using & of rendering to others to be used the said machine for fourteen years & in order to convince the board that your petitioners wish is to encourage the using a machine of such consequence to the Country & that it will not cost a high price for spinning he will submit to the consideration of the board the price for spinning he shall demand after observing that the price for spinning of the machine which Sir Richard Arkwright obtained a Patent for was five guineas & although his Patent is now expired your petitioners well informed they are still sold for one guinea pr. spindle & a Patent has lately been granted in England to Messrs. Henderon & Porthouse for a machine for spinning fine & long combed wool, these Gentlemen sell their spindles at 24 1/2 pr. spindle and that the cost work is higher here than in England.

And your Petitioner shall ever pray

Henry Ward.
